UNITED STATES PATENT OFFICE

THOMAS A. DIMETROFF, OF FREEMAN, WASHINGTON

RAIL NIPPER

Application filed December 3, 1930. Serial No. 499,832

This invention aims to provide a novel fulcrum member, adapted to support a bar, which is used to raise a railroad rail, so that a tie plate can be slid under the rail.

5 It is within the province of the disclosure to improve generally and to enhance the utility of devices of that type to which the invention appertains.

With the above and other objects in view, 10 which will appear as the description proceeds, the invention resides in the combination and arrangement of parts and in the details of construction hereinafter described and claimed, it being understood that changes 15 in the precise embodiment of the invention herein disclosed, may be made within the scope of what is claimed, without departing from the spirit of the invention.

In the accompanying drawings:

20 Figure 1 shows in elevation, a device constructed in accordance with the invention, parts being broken away;

Figure 2 is a top plan;

25 Figure 3 is a bottom plan of the fulcrum member;

Figure 4 is an elevation of the fulcrum member;

Figure 5 is a section on the line 5—5 of Figure 2.

30 The numeral 1 marks the railroad tie, and the numeral 2 designates the railroad rail. The numeral 3 indicates a tie plate. The numeral 4 designates a bar, which, being introduced under the ball of the rail 2, is used 35 to raise the rail, so that the tie plate 3 can be slid to place between the tie 1 and the rail 2.

For the support of the bar 4 there is provided a fulcrum member, including a flat 40 metal plate 5 provided near to its forward edge with a plurality of holes 6. Parallel slits 7 are formed in the plate 5 in advance of the holes 6, the slits 7 communicating with the holes 6. The material freed in the formation of the slits 7 is forced downwardly, as 45 in Figure 5, to form downwardly extended, rearwardly inclined, pointed prongs 8.

The fulcrum member includes an inverted, 50 U-shaped metal bracket comprising downwardly diverging legs 9 having outwardly

extended feet 10 connected by securing elements 11 with the base plate 5. The upper ends of the legs 9 are connected by a saddle 12. The saddle 12 is upwardly convexed, as shown at 14, from front to back, and is concaved, as shown at 15 from side to side. The bracket is forwardly inclined, as shown at 16, to overhang the forward edge of the base plate 5.

55 In practical operation, the bar 4 is engaged under the ball of the rail 2, and is mounted, intermediate its ends, in the saddle 12 of the fulcrum member. Because the saddle 12 is upwardly convexed from front to back as shown at 14, the bar 4 can rock readily on the saddle. Because the saddle is concaved, as shown at 15, from side to side, the bar will not readily slip off the saddle, sidewise. The bracket of the fulcrum member is forwardly inclined at 16, and the prongs 8 are downwardly and rearwardly inclined, as shown in Figure 5. The result is that when pressure is put on the bar 4, to lift the rail 2, there is a tendency to slide the fulcrum member, as a whole, backwardly, a little, and thereby embed the prongs 8 in the tie 1, the backward movement of the fulcrum member thus being stopped, and the fulcrum member remaining securely in place, as a support for the bar 4.

60 If, for any reason, it is desired to fasten the base plate down permanently, it can be done by driving spikes through the exposed holes 6 of Figure 2. Ordinarily, however, and in the operation shown in Figures 1 and 2, there is no occasion for spiking down the base plate, prongs 8 being entirely adequate to hold the plate against backward movement. It is only in unusual jobs, or where the fulcrum member is to remain in place for a 65 long time that it may be desirable to spike it down through the holes 6.

70 The device forming the subject matter of this application, is simple in construction, but it will be found thoroughly effective to support a bar, such as the bar 4, when new ties have been put in, and when it is necessary to raise the rail, in order that the tie plates may be slid under the rail.

75 The structure hereinbefore described, will be found to be of peculiar utility in replac-

ing tie plates during the process of putting in new ties.

Having thus described the invention, what is claimed is:

5 In a device for raising railroad rails, a fulcrum member comprising a base plate and an upstanding bracket on the base plate, the bracket being provided at its top with a saddle which is upwardly convexed from front to back, and concaved from side to side.

10 In testimony that I claim the foregoing as my own, I have hereto affixed my signature.

THOMAS A. DIMETROFF.
